UNITED STATES PATENT OFFICE.

JOHN GIBBONS, OF WEST TROY, AND CHARLES D. MENEELY, OF ALBANY,
ASSIGNORS TO THE MENEELY HARDWARE COMPANY, OF WEST TROY,
NEW YORK.

BICYCLE.

SPECIFICATION forming part of Letters Patent No. 351,972, dated November 2, 1886.

Application filed July 23, 1885. Serial No. 172,393. (No model.)

To all whom it may concern:

Be it known that we, JOHN GIBBONS, of the village of West Troy, county of Albany, State of New York, and CHARLES D. MENEELY, of the city of Albany, county and State aforesaid, have jointly invented new and useful Improvements in Bicycles, of which the following is a specification.

Our invention relates to bicycles, and more particularly to that class of them which are made with two wheels of equal size, that are placed side by side, with the rider's seat arranged between them and below the axle journals, the principal objects of our invention being to check and control the speed of the bicycle as desired, to change the direction of its motion, and to better operate this class of bicycles to obtain a high rate of speed.

Accompanying this specification, to form a part of it, there are two plates of drawings, containing six figures, illustrating our invention, with the same designation of parts by letter-reference used in all of them.

Of these illustrations, Figure 1 is a perspective of a bicycle containing our invention and improvements. Fig. 2 is a longitudinal vertical section taken through a part of the treadle-crank shaft, a sleeved sprocket-wheel that is arranged to turn on or with said shaft, and adapted to engage with a friction-wheel that is keyed to said shaft for receiving power therefrom, a spiral spring arranged on said treadle-crank shaft to force the side of said sprocket-wheel to contact with the adjacent side of the friction-wheel, a part of one of the hangers which at its upper end attaches to the bicycle-axle and at its lower end is constructed with a bearing for the treadle-crank shaft, a collar on the latter at each side of the said bearing, and a cap inclosing that one of the said collars which is adjacent to the inner end of the spiral spring, all the parts shown in this figure being illustrated in a larger representation than at Fig. 1, wherein the same parts are shown in oppositely-arranged duplication in connection with each end of the treadle-crank shaft. Fig. 3 shows a side elevation of one of the friction-wheels with the rubber cheeks omitted. Fig. 4 shows in a side

elevation, and as separated from the axle of 50 the bicycle, one of the treadle-crank-shaft hangers and the connected lever for operating one of the brakes, of which there is one arranged on the hub of each of the bicycle-wheels. This view shows also a part of one 55 of the brake-wheels, the lever for operating one of the brakes, showing also the levers for operating the shipper to move one of the sprocket-wheels away from its engagement with the adjacent one of the friction-wheels. 60 This figure shows also in elevation a part of the rim of one of the friction-wheels, a part of one of the sprocket wheels, the cap of the friction-wheel being shown in section. Fig. 5 shows an elevation of one of the brake-wheels 65 illustrated as separated from the hub. This figure shows also the brake-arm to which the lever connects that operates said brake, said parts being shown with what is their inner face turned toward the sight. Fig. 6 shows an 70 elevation of one of the sprocket-wheels and the shipper arranged to engage with a groove formed in its hub, this illustration being taken with the hub-face of the sprocket-wheel turned toward the sight. 75

The several parts of the mechanism thus illustrated are designated by letter-reference and the function of the parts is described as follows:

The letters W W indicate the wheels on 80 which the device moves. These wheels are of the same size and are arranged side by side. They are constructed to turn on the axle A, the latter being dropped down centrally at or nearly at right angles to the journals to form 85 the seat for the wheelman, the seat being designated at S' and the back at B.

The letters H indicate the hubs of the wheels, which are made with the sprocket-grooves G, and these hubs each have arranged thereon inside of said sprocket-grooves the brake-wheels R, the rims of which are grooved out to receive the brake B'.

The letters D' indicate hangers, of which there is one each side of the seat, and these hangers are at their upper ends each attached to the axle, as indicated at m', and therefrom projected downwardly, and at their lower ends

each constructed with a bearing, b^2 , for the treadle-crank shaft T, the latter being made with the treadles t^1 .

The letters S^2 indicate sprocket-wheels, of which there is one at each side of the treadles on the treadle-crank shaft. These sprocket-wheels are made with the offset hubs h^2 on their inner sides, and the letters g^2 designate a groove formed in revolution on the exterior of each of said hubs to receive the sprocket-wheel shipper N. Each of these sprocket-wheels is made with the sleeved-out part π^2 in its hub end, and each of these sprocket-wheels is provided with a chain-belt, C, that connects with one of the sprocket-grooves made in the hub of each of the wheels W. These sprocket-wheels are arranged to turn on the treadle-crank shaft T when they are not in an impressed contact with one of the friction-wheels F. The friction-wheels F are each made with openings O, that have inwardly-beveled faces to their sides that are adapted to receive the wedge-form cheeks K, preferably made of rubber. The inner ends of these cheeks, when arranged to make friction engagement with one of the sprocket-wheels at the outer side of the latter, project beyond the body of the wheel-body b^5 at e, and these cheeks are secured within the wheels F by means of a cap, C², that covers the outer face of said wheel and extends over its rim to be secured therewith. These friction-wheels are keyed to the treadle-crank shaft, so as to turn with the latter, as indicated at K². There is one of these friction-wheels and one of these sprocket-wheels at each end of the treadle-crank shaft.

The letter S³ indicates a spiral spring, of which there is one at each side of the treadles, and each of the said springs is constructed to encircle the treadle-crank shaft immediately outside of the bearings of the latter, and so arranged therewith that one end of each spring shall be within the sleeved part of the sprocket-wheel hub to bear against the latter, and the other end of each of the springs to abut against the cap v, inclosing the collar M', with the recoil force of each spring adjusted so as to press the sprocket-wheel at each end of the treadle-crank shaft against the friction-wheel therewith.

The letters R designate brake-wheels, as before described, and L' levers, of which there is one at each side of the seat. These levers L' are each of them pivoted to one of the hangers D' at p', and at the other end each of these levers is loosely pivoted to the brake-arm a³, the latter being connected with the brake B², so that when the handle end l' of the lever L' is pressed down at either side of the seat the brake upon that side is forced up to engage with the brake-wheel to arrest the speed of the bicycle.

The letters L² designate another lever at each side of the seat, and each of these last-named levers is pivoted to one of the hangers,

D', at p². These levers L² are at their ends pivoted at p³ to a lever-bar, l', and the latter at its lower end to the angular turn lever l' at p⁴, the latter being centrally pivoted at p⁵ to an offset, O⁴, on the hanger D', the lower arm of said angular turn-lever being connected to the shipper N, so that when the lever L² on its handle end e² is pressed down at either side of the seat, the shipper connected therewith moves out the connected sprocket-wheel from its friction engagement with the wheel F, and the sprocket-wheel thus moved away from its engagement against the force of the spring S³, ceases to act on the chain-belt of that one of the wheels with which its chain connects, causing the bicycle to turn and pivot in its turning on the wheel thus arrested. When such a turn has been made, on releasing the lever L² the spring S³ immediately forces the detained sprocket-wheel to engage with the friction-wheel, and motion is again communicated to the wheel of the bicycle on which the turn has been made.

Each of the levers, L², where pivoted to the lever-bars l', is projected upwardly and forked, as shown at y, Fig. 5, in an enlarged representation, the fork y embracing the lower end of the brake-arm a³, so that when one of the shippers N is actuated to arrest the rotation of either of the sprocket-wheels as the inner end of said lever L² is pressed down to operate the shipper the brake at the same side of the seat is also put on by the upward movement of the bracket end and its engagement with the brake-arm a³. Though the brake at each side may be operated independently of the shipper N, yet the latter cannot be operated without also operating the brake.

The bicycle is moved by the wheelman operating with his feet the treadles, the latter communicating motion to the shaft T by means of the treadle-cranks, and the shaft T to the friction-wheel F, the rubber cheeks K of the latter being held close against the outer face of the sprocket-wheels S² by the action of the spring S³, so that motion is communicated to the chains C by means of said sprocket-wheel, and this motion is transmitted to the wheels W by means of the sprocket-grooves G in the hubs of the wheels, as before described. When it is desired to arrest the speed of the bicycle, the levers L' are pressed down, which brings into action the brakes. When it is desired to change the direction of the bicycle, it is done by operating the lever L² to put on the brake, and to disconnect one of the sprocket-wheels from the friction-wheel F on that side of the bicycle necessitated to make the shortest curve in turning.

While we have described the cheeks K as made of rubber, and the function of these cheeks is merely to cause a friction engagement between the inner face of the wheel F, to communicate motion by contact to the adjacent sprocket-wheel, any equivalent material

or mechanism that will perform this function in substantially the same manner may be employed.

Having thus described our invention, what we claim, and desire to secure by Letters Patent, is—

1. The combination, with the wheels W W, each made with the grooves G, and the brake-wheels R upon the inner ends of their hubs, of the hangers D' D', each made with the bearings b², the treadle-crank shaft T, made with the treadles t', said treadle-crank shaft having arranged thereon at each end outside of said treadles the sprocket-wheel S², friction-wheel 15 F, and the spring S³, the belt-chains C' C', the lever L', arranged upon each of said hangers, and the brakes B² B², each connected with one of said levers, all constructed and arranged to operate substantially in the manner and for 20 the purposes set forth.

2. In a bicycle, the combination of the two wheels W W, of equal size, arranged side by side, and constructed with sprocket-grooves on the inner ends of their hubs, the axle A, made 25 with the downcast seat S', the hangers D', made with the bearings b², the treadle-crank shaft T, made with the treadles t', said shaft having arranged thereon at each end outside of the treadles the spring S³, sprocket-wheel S², and 30 the friction-wheel F, the belt chains C' C', the

levers L², made with the forked ends y, the lever-bars l', turn-lever l', and shipper N, arranged to operate substantially as and for the purposes set forth.

3. In a bicycle, the combination of two 35 wheels of equal size arranged side by side, and constructed with sprocket-grooves on the inner ends of their hubs, an axle provided with journals for said wheels, and a downcast seat, hangers at each side of said seat, constructed 40 with bearings at their lower ends, a treadle-crank provided with foot-treadles, a friction-wheel at each end of said treadle-crank shaft constructed to turn with the latter, a sprocket-wheel arranged on said treadle-crank shaft 45 to be operated by each of said friction-wheels, a spring arranged on said shaft at each side of said treadles between the latter and the friction-wheel, and a chain-belt connecting the sprocket-grooves of each of the hubs with one 50 of said sprocket-wheels, substantially as shown and described.

Signed at Troy, New York, this 9th day of July, 1885, and in the presence of two witnesses, whose names are hereto written.
